LATCH MECHANISM

Trygve Vigmostad, Detroit, Mich., assignor to
 Briggs Manufacturing Company, Detroit, Mich.,
 a corporation of Michigan

Application June 10, 1949, Serial No. 98,306

12 Claims. (Cl. 292—7)

1

The present invention relates to a vehicle body of the convertible type having a collapsible or foldable top and in particular to improved latch means for locking the top in the closed or cover position to rigid parts of the body structure.

Important objects of the present invention are to provide a motor vehicle body of the convertible type having improved means for positively locking and unlocking the convertible top to the body; and to provide such a locking means which is simple in construction, safe and dependable in operation, and comparatively inexpensive to manufacture and install.

Another object of the invention is to provide an improved locking means between a convertible motor vehicle body and the collapsible or foldable top thereof which is readily accessible for unlocking from the interior of the body and which automatically locks upon movement of the top to the closure or cover position.

Another object is to provide an improved locking means of the foregoing character including a plurality of locking devices which may be quickly and easily operated from the driver's seat by means of a single control lever or handle and which assures a positive secure locking between the top and body in the closed or cover position of the top.

Still another object is to provide such a construction wherein the handle is normally yieldingly held in a comparatively inconspicuous out of the way rest position; being readily accessible to the operator for operation and being thereafter returned automatically to the rest position independently of the locking means upon being released by the operator. Accordingly a projecting handle in the operative position is avoided at all times except when the same is initially employed to unlock the top.

Other objects of this invention will appear in the following description and appended claims, reference being had to the accompanying drawings forming a part of this specification wherein like reference characters designate corresponding parts in the several views.

Details of a preferred embodiment of the present invention are shown by way of example in the drawings wherein:

Fig. 1 is a fragmentary perspective view of a portion of the interior of the convertible type vehicle body, showing the convertible top header and the manually controlled lever for unlocking the lock means of the present invention.

Fig. 2 is a fragmentary enlarged section taken in the direction of the arrows substantially along

2

the line 2—2 of Fig. 1, showing the lock mechanism in the locked position.

Fig. 3 is a vertical center line section through selected pivotal connections of the operating mechanism taken substantially in the direction of the arrows along the broken line 3—3 of Fig. 2.

Fig. 4 is a fragmentary vertical section taken in the direction of the arrows substantially along the line 4—4 of Fig. 2.

Fig. 5 is a fragmentary enlarged section similar to Fig. 2, showing the lock mechanism in the unlocked position.

Fig. 6 is a fragmentary vertical section taken in the direction of the arrows substantially along the broken line 6—6 of Fig. 5.

Fig. 7 is a fragmentary enlarged section taken in the direction of the arrows along the line 7—7 of Fig. 2.

Fig. 8 is a fragmentary section taken in the direction of the arrows along the line 8—8 of Fig. 2.

Before explaining the present invention in detail it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation.

Referring to the drawings, a convertible type automobile body indicated generally by the numeral 10 is shown with a windshield 12 located within a rigid V-type frame or casing 14 suitably secured to the body 10 to comprise an integral structure therewith. The body 10 is also provided with a collapsible or foldable top 16 of any suitable material, such as canvas for example, which may be suitably secured in accordance with conventional practice to folding side rails 18 of the top frame and to a forward rigid transverse top header indicated generally by the numeral 20.

The latter is suitably secured at its opposite ends to the forward ends of the side rails 18 and is preferably a hollow construction comprising upper and lower sheet steel stampings 22 and 24 respectively, Fig. 3. In general, the stampings 22 and 24 extend the length of the header 20 and are shaped to form a closed box section of any suitable shape and dimensions adequate to contain the lock or latch mechanism described hereinafter and to conform to the structural requirements and style of the vehicle body.

The lower stamping 24 is generally L-shaped

in section to provide a base portion and an upright back portion and is secured along its longitudinal edges, as by welding for example, at 26 and 28 to the longitudinal edges of the upper stampings 22, Fig. 3. The exterior surface of the latter is generally arcuate from front to rear and is provided with forward and rearward channels 22a and 22b respectively which extend longitudinally of the header 20 and are adapted to receive tacking strips, not shown, to which the flexible 10 top material 16 is tacked in accordance with conventional practice.

As indicated in Fig. 2, the header 20 is of the conventional flat V-type conforming to the divided V-type windshield 12 and having arms of reduced width extending laterally and rearwardly from a portion of maximum width at the apex of the V. The upper portion of the windshield frame 14 provides a rigid seat or abutment, to which the base portion of the header stamping 24 is seated when the convertible top is in the raised or closed position, and is provided with a fixed upright central dowel or pin 30 and a pair of fixed upright lateral dowels 32 located near the ends of the frame 14. A central perforation 31 reinforced by a grommet 39 is provided in the base portion of the stamping 24 to receive the dowel 30. Similar perforations 33 are provided in the lateral base portions of the stamping 24 to receive the dowels 32. Further details of the body and top frame construction are not pertinent to an understanding of the present invention and are accordingly not described herein.

In accordance with the objects of the present invention, improved locking or latching means are provided for engaging the dowels 30 and 32, whereby the header 20 may be conveniently and positively locked tightly and rigidly to the upper seat or abutment provided by the frame 14. The locking or latching means in the preferred construction shown employs a pair of tubular locking rods 34, each extending longitudinally within one of each of the hollow V-arms of the header 20 and terminating short of the corresponding dowel 32. Inserted into the distal end of each tubular rod 34 is the stem or shank 36 of a wedge member 38, which projects from the arm 34 and tapers to a pointed nose adapted for insertion into or withdrawal from a corresponding tapered wedge opening 40 provided within the adjacent dowel 32 upon lateral extension or retraction respectively of the rod 34, Fig. 8. The shank 36 is secured within the tubular end of the arm 34 by a suitable screw or retaining pin 42, Fig. 8.

Operation of the rods 34 is effected by pivotal movement of a coupling 44, Fig. 2, pivotal about a fixed upright stud 46 within the enlarged portion of the V-base of the header 20 and being also pivotally connected at 48L and 48R on opposite sides of the pivot 46 to the flattened proximal ends 56L and 56R respectively of the rods 34 within the left and right V-arms respectively of the header 20.

Each arm 34 is supported and guided in its retracting and extending movements by a pair of similar spaced upright brackets 52 and 54 having leg portions 56 and 58 respectively secured to the base portion of the lower stamping 24, as by welding for example. The brackets 52 and 54 of each pair may conveniently comprise sheet metal stampings and are formed with perforations 60 and 62 respectively enclosed by flange collars 64 and 66 respectively through which pass the rod 34. As indicated in Fig. 2, the perfora-

tions 60 and 62 are preferably slightly elongate from front to rear of the automobile body to permit limited forward and rearward movement as required of the arms 34 in their operation. The vertical diameters of the perforations 60 and 62 are determined to minimize vertical play or movement of the rod 34 passing therethrough and are no larger than required to permit freedom of longitudinal movement of the rods 34.

In order to assure a positive rattle proof engagement between the dowels 32 and the wedge tips 38 within the openings 40 provided therefor, each arm 34 is resiliently urged to its laterally extending position by a coil spring 68 under compression between the upright portion of the bracket 52 and an annular seat 70 of a retaining bracket 72 suitably secured by means of a pin 74 to the arm 34 at a location intermediate the brackets 52 and 54. The proximal end 20 of each spring 68 is seated against the upright portion of the corresponding bracket 52 above and below the perforation 60 therein. By virtue of the force of the spring 68 exerted on the arm 34, and the fact that the latter is attached 25 wedge tip 38 are held against vertical movement within the perforations 60 and 62, the cam action between the inclined upper surfaces of the tips 38 and the orifices 40 will force the header 20 in the closed position, Fig. 8, firmly downward 30 toward the abutment surface of the frame 14.

The aforementioned pivot pin 46 for the coupling 44 extends upright from a raised platform 76 of a generally L-shaped supporting bracket 78. The latter is adapted to conform to the interior contour of the lower header stamping 24 and is suitably secured thereto as by welding for example. The lower portion of the pin 46 projects through the platform 76 and is peened or expanded against the underside thereof at 80. Above the platform 76 and around the body of the pin 46 is an annular spacer 82 on which the body of the coupling 44 is supported in a desired position with respect to the central pin or dowel 30.

Referring to Fig. 4, the dowel 30 is provided with a notch 84 in one side thereof having an upper cam surface 86 inclined outward from the base of the notch 84. Projecting forward from the coupling 44 in the locking position is a locking arm 88, Figs. 2 and 4, having a declined cam extension 90 adapted to be inserted into the notch 84 and interlocked with the inclined upper surface 86 thereof so as to assist the wedge tips 38 in drawing the header 20 downward and locking the same to the upper abutment surface of the frame 14 upon closure of the top, as described hereinafter. Accordingly, upon counterclockwise pivoting of the coupling 44 from the position of Fig. 2 to the position of Fig. 5, the connected latching mechanism including the arm 88 and rods 34 move from the latching to the unlatching position.

Also integral with the coupling 44 and extending perpendicularly to a radial element thereof is an upright edge or flange located substantially on the side of the pivot 46 opposite the locking arm 88 and providing a vertical abutment or shoulder 92, a horizontal ledge 94 at the top of the shoulder 92, and a detent shoulder or hook portion 96 extending upright from the ledge 94 at a location suitably spaced from the shoulder 92 in the general direction of counterclockwise pivotal movement of the coupling 44. A cam edge 98 declines from the upper portion of the shoulder 96 to the plane surface of the coupling 44 in

the aforesaid general direction of counterclockwise pivotal movement, Figs. 2 and 7.

In order to engage and retain the shoulder 96 in the unlatching position, a spring strip or resilient keeper member 100 is suitably secured at one end to the pin 46 and extends radially therefrom to the upper end of a vertically movable operator 102. In the present instance, the pin 46 passes through a perforation in the aforesaid end of the spring strip 100 so as to anchor that end of the spring 100 against movement. The other end of the spring strip 100 comprises a yoke 104 having arms thereof spaced by the operator 102 and formed around the opposed ends of a retaining pin 106 in such a manner as to provide an elongated lost motion loop 108 within which the pin 106 is retained and movable longitudinally of the strip 100. The pin 106 extends horizontally through and projects from opposite sides of the upper portion of the operator 102 to complete a coupling between the latter and the spring strip 100. The lower portion of the operator 102 passes downward through an annular guide eyelet 110 which projects vertically upward through an opening provided therefor within the lower header stamping 24 and is suitably secured to the latter by means of a base flange 112.

The spring 100 is biased for normally holding the operator 102 in a downward or detent position with its lower extremity projected below the base portion of the header stamping 24. An abutment 114 preferably of rubber or resilient material is suitably secured to the upper portion of the frame 14 underlying the operator 102 so as to force the same upward within the guide eyelet 110 upon closure of the vehicle top 16. The stamping 24 is recessed at 116 to receive the abutment 114 when the header 20 is closed against the frame 14, Fig. 6.

Referring particularly to Figs. 2 and 5, it is to be observed from the construction described thus far that the proximal ends 50L and 50R of the left and right locking rods 34 respectively are pivotally secured to the coupling 44 at points 48L and 48R on substantially opposite sides of the pivot 46. Also substantially diametrically opposed and at locations intermediate the pivotal connections 48L and 48R are the locking arm 88 and detent shoulder 96.

The above mechanism is preferably arranged so that upon pivoting the coupling 44 substantially a quarter turn counterclockwise about the pivot 46, both rods 34 will be retracted against the tension of the coil springs 68 to an unlatched or unlocked position, whereat the wedge tips 38 are withdrawn from interlocking engagement with the wedge openings 40 of the lateral studs 32. Simultaneously, the cam edge or flange 90 of the arm 88 is withdrawn from interlocking engagement with the cam edge 86 of the central pin 30. In the same action, the declined cam edge 98 under-rides the spring strip 100 so as to position the detent shoulder 96 forward of the spring strip 100. Thus as the header 20 is raised from its closed position abutting the frame 14, the spring 100 will move the operator 102 downward through the eyelet 110 to the detent position, whereat the portion of the spring 100 adjacent the shoulder 96 will be below the upper edge of the latter, Fig. 6, to prevent clockwise return of the coupling 44 to the locked position. Upon closure of the convertible top 16, so that the header 20 snugly abuts the frame 14, the operator 102 will contact the pad 114 and raise the spring 100 above the shoulder 96

to permit automatic return of the coupling 44 to the locked position as discussed hereinafter.

Actuation of the pivotal coupling 44 to the unlatching position is readily accomplished in the present instance by means of a control lever 118 located externally to the header 20 and manually operative by the driver or front seat passenger. Referring particularly to Figs. 2, 3 and 5, the handle 118 is provided with a central rounded body portion 120 pivotally connected rearwardly of the header 20 to a pair of vertically spaced upper and lower brackets 122 and 124 respectively by means of a vertical pivot pin 126. The forward portion of the flange 122 extends through aligned openings 128 and 130 within the upright portions of the header stamping 24 and reinforcing bracket 78 respectively and bends upward in a flange 132 adjacent the forward or inner surface of the reinforcing bracket 78. Similarly the lower bracket 124 extends through the aligned openings 128 and 130 below the handle body portion 120 and bends downward in a flange 134 adjacent the forward surface of the reinforcing bracket 78. The major portion of the rounded handle body 120 is concentric with the axis of the pivot 126 and is enclosed within a housing 136 having an opening 138 therein through which the lever 118 extends into the vehicle body, Fig. 1. The housing 136, bracket portions 132 and 134, and the upright portions of the header stamping 24 and bracket 78 are suitably secured together as for example by a plurality of screws 140.

Integral with the body 120 and extending inward therefrom at a generally obtuse angle to the lever 118 is a lever arm 142 which is pivotally connected by a pin 144 to one end of a connecting link 146, Figs. 2, 5, and 6. The other end of the link 146 is pivotally connected by a pin 148 to one end of a driving link 150. The other end of the link 150 is apertured to fit over the upper end of the pivot stud 46, Fig. 3, for pivotal connection therewith.

The link 150 is pivotally secured to the stud 46 above the coupling 44 and below the spring strip 100 at the desired height to abut the shoulder 92 in driving engagement therewith as explained below. The link 150 is spaced from the spring 100 by a nut 152 screwed onto an upper screw threaded portion 153 of the pin 46. Interposed between the link 150 and coupling 44 is a washer 154.

The disposition and dimensions of the link 150, activating arm 142, and link 146 are determined so that the outer end of the link 150 is positioned adjacent the abutment or shoulder 92 of the coupling 44, whereby the latter will be driven counterclockwise by the link 150 upon clockwise pivoting of the handle 118 about the pivot 126. As indicated in Figs. 2 and 5, upon clockwise pivoting of the handle 118, the connected links 146 and 150 are driven counterclockwise. The outer end of the link 150 abutting the shoulder 92 will then drive the latter and the coupling 44 counterclockwise around the stud 46 so as to position the aforementioned detent shoulder 96 forward of the spring strip 100, whereat upon downward movement of the operator 102, the spring 100 will block the return or latching movement of the coupling 44.

Return of the lever 118 from the position shown in Fig. 5 to the rest position shown in Fig. 2 is permitted independently of the pivotal movement of the coupling 44 by means of a clock type spring 156 having one end engaged within a

transverse slot 158 extending longitudinally of the upper portion of the stud 46. From the slot 158, the spring 156 completes one or more counterclockwise spirals under tension around the body of the stud 46 and terminates in a hook attachment around the upper flanged extension 148a of the pin 148, urging the links 150 and 146 clockwise about the pivot stud 46. Thus after the handle 118 is moved to the unlatching position of Fig. 5 and is released by the operator, it will be resiliently returned to the initial rest position of Fig. 2. The end portion of the coiled spring 156 inserted within the slot 158 rests upon the strip spring 100 and is suitably retained from above by a washer 160 and nut 162 screwed on the upper threaded extension 153 of the stud 46.

It is apparent from the foregoing that when the convertible top 16 is in the closed position, with the header 20 abutting the upper portion of the frame 14, the fixed locking pins or dowels 30 and 32 will project into the hollow interior of the header 20 through their corresponding openings 31 and 33 in position for engagement respectively by the cam edge 90 of the locking arm 88 and the wedge tips 38 when the latch mechanism is in the latched position, i. e., in the extended position of the arms 34 and the clockwise position of the coupling 44, Fig. 2. In this position, the lower portion of the operator 102 is in abutting engagement with the pad 114 and the spring strip 100 is in the elevated or releasing position, Fig. 6. At this position of the latching mechanism, the header 20 will be positively and securely latched to the frame 14 by virtue of the aforementioned interlocking camming engagement between the wedge tips 38 and openings 40 therefor within the dowels 32, and between the cam flange 90 and inclined surface 86 of the dowel 30. The tension of the coil springs 68 is exerted continuously to extend the locking rods 34 and hold the same forcibly in locking interengagement with the dowels 32. Play and rattling of the rods 34 and also counterclockwise rotation of the coupling 44 from the latching position are thus effectively prevented.

Unlatching of the header 20 from the frame 14 is readily permitted by the driver or other front seat occupant merely by reaching forward and pulling the lever 118 rearward, i. e. clockwise about the pivot 126, thereby pivoting the coupling 44 counterclockwise to the unlatching position as described above, retracting the locking wedges 38 and 90 from their respective dowels 32 and 30 against the tension of the coil springs 68. At the same time, the detent shoulder 96, is positioned forward of the leading edge of the spring strip 100. While holding the handle 118 in the unlatching position, the header bar 20 may be raised from the frame 14, permitting downward movement of the spring pressed operator 102 and the spring strip 100. The leading edge of the latter will thus be lowered below the upper portion of the detent shoulder 96 in position to engage the same and prevent return or clockwise movement of the coupling 44 to the latching position upon subsequent release of the handle 118. Accordingly, the latter may be released immediately after elevating the header 20 a short distance from the frame 14, whereupon the handle 118 will be returned to the position of Fig. 2, independently of the coupling 44 which is retained in the unlatched position, Fig. 5. The convertible top may then be folded into a compartment at the rear of the vehicle body in accordance with conventional practice.

When it is desired to close the convertible top, the latter is unfolded and brought forward in a closure action from the compartment at the rear of the vehicle until the header 20 snugly abuts the frame 14. In this action the studs 30 and 32 will re-enter their respective openings 31 and 33 within the header base 24. Simultaneously the lower extremity of the finger 102 will engage the pad 114 and be elevated thereby to the position of Fig. 6, raising the keeper spring 103 to the releasing position above the uppermost tip of the detent shoulder 96 and freeing the latter and integral coupling 44 for clockwise rotation to the latching position as urged by the coil springs 68. Upon clockwise rotation of the coupling 44, the cam flange 90 is moved into interlocking engagement with the notch 86 of the dowel 30 and the locking rods 34 are extended so as to project the wedge tips 38 into the wedge openings 40 of the dowels 32. Thus, upon closure of the automobile top, the header 20 is automatically locked to the abutment frame 14 without effort or concern upon the part of the operator.

23 I claim:

1. In a latch means for a convertible top movable between folded and cover positions with respect to a vehicle body, a pair of oppositely shiftable bolt members for latching said top in the cover position, spring means associated with said bolt members for urging the same into latching positions, pivotally mounted coupling means interposed between and pivotally connected to adjacent portions of said bolt members, a pivotally mounted control lever movable from a rest position to pivotally actuate said coupling means and thereby retract said bolt members to their unlatching positions, a detent movable with said coupling means, a keeper member movable into and out of detent holding position for holding the detent in position to maintain said bolt members in their unlatching positions, and a shiftable member engageable with a part of the vehicle body upon unfolding of the top to the cover position for moving said keeper member out of the detent holding position.

2. In a latch means for a convertible top movable between folded and cover positions with respect to a vehicle body, a pair of oppositely shiftable bolt members for latching said top in the cover position at laterally spaced locations, spring means associated with said bolt members for urging the same into latching positions, a unitary pivotally mounted coupling member interposed between and pivotally connected to adjacent portions of said bolt members, a third bolt member carried by said coupling member and movable therewith into and out of latching position to latch the top at a locality intermediate the first named bolt members, a pivotally mounted control lever movable from a rest position to pivotally actuate said coupling member and thereby retract said bolt members to their unlatching positions, a detent movable with said coupling member, a keeper member movable into and out of detent holding position for holding the detent in position to maintain said bolt members in their unlatching positions, and a shiftable member engageable with a part of the vehicle body upon unfolding of the top to the cover position for moving said keeper member out of the detent holding position.

3. In a latch means for a convertible top movable between folded and cover positions with respect to a vehicle body, a pair of oppositely

shiftable bolt members for latching said top in the cover position, spring means associated with said bolt members for urging the same into latching positions, pivotally mounted coupling means interposed between and pivotally connected to adjacent portions of said bolt members, a pivotal control lever for said coupling member movable from a rest position to actuate the coupling member to retract said bolt members to their unlatching positions, spring means for automatically urging return of the lever to its rest position, a detent movable with said coupling means, a keeper member movable into and out of detent holding position for holding the detent in position to maintain said bolt members in their unlatching positions, and a shiftable member engageable with a part of the vehicle body upon unfolding of the top to the cover position for moving said keeper member out of the detent holding position.

4. In a latch means for a convertible top movable between folded and cover positions with respect to a vehicle body, a pair of oppositely shiftable bolt members for latching said top in the cover position, spring means associated with said bolt members for urging the same into latching positions, pivotally mounted coupling means interposed between and pivotally connected to adjacent portions of said bolt members, a pivotally mounted control lever movable from a rest position to pivotally actuate said coupling means and thereby retract said bolt members to their unlatching positions, a detent movable with said coupling means, resilient means movable vertically to or from a detent holding position and having a portion engageable at that position with said detent to hold the same in position to maintain said bolt members in their unlatching positions, and a vertically shiftable member engageable with a part of the vehicle body to be shifted vertically thereby upon unfolding of the top to the cover position and also engageable with the resilient means upon being shifted vertically by engagement with the vehicle body to move the latter means out of the detent holding position.

5. In a latch means for a convertible top movable between folded and cover positions with respect to a vehicle body, a pair of oppositely shiftable bolt members for latching said top in the cover position, spring means associated with said bolt members for urging the same into latching positions, pivotally mounted coupling means interposed between and pivotally connected to adjacent portions of said bolt members, a pivotally mounted control lever movable from a rest position to pivotally actuate said coupling means and thereby retract said bolt members to their unlatching positions, a detent movable with said coupling means, vertically shiftable means on the top including a resilient portion and being yieldingly supported at a detent position in the path of movement of said detent to hold said bolt members in their unlatching positions, a portion of said shiftable means engaging said vehicle body to be shifted thereby from the detent position upon unfolding of the top to its cover position into engagement with said body.

6. In a latch means for a convertible top movable between folded and cover positions with respect to a vehicle body, a pair of oppositely shiftable bolt members for latching said top in the cover position, spring means associated with said bolt members for urging the same into latching positions, pivotally mounted coupling means interposed between and pivotally connected to

adjacent portions of said bolt members, a pivotally mounted control lever, link means connecting the lever and coupling means to actuate the latter to retract said bolt members to their unlatching positions upon pivoting of the lever from a rest position, spring means acting on said link means to return the lever to its rest position upon release of the lever, a detent movable with said coupling means, a keeper member movable into and out of detent holding position for holding the detent in position to maintain said bolt members in their unlatching positions, and a shiftable member engageable with a part of the vehicle body upon unfolding of the top to the cover position for moving said keeper member out of the detent holding position.

7. In a latch means for a convertible top movable between folded and cover positions with respect to a vehicle body, a pair of oppositely shiftable bolt members for latching said top in the cover position, spring means associated with said bolt members for urging the same into latching positions, pivotally mounted coupling means interposed between and pivotally connected to adjacent portions of said bolt members, a pivotally mounted control lever, link means connecting the lever and coupling means to actuate the latter to retract said bolt members to their unlatching positions upon pivoting of the lever from a rest position, spring means yieldingly urging return of the lever to its rest position, a detent movable with said coupling means, vertically shiftable means on the top including a resilient portion and being yieldingly supported at a detent position in the path of movement of said detent to hold said bolt members in their unlatching positions, a portion of said shiftable means engaging said vehicle body to be shifted thereby from the detent position upon unfolding of the top to its cover position into engagement with said body.

8. In a latch means for a convertible top movable between folded and cover positions with respect to a vehicle body, a pair of oppositely shiftable bolt members for latching said top in the cover position, spring means associated with said bolt members for urging the same into latching positions, pivotally mounted coupling means interposed between and pivotally connected to adjacent portions of said bolt members, a pivotally mounted control lever, abutment means movable with the lever and releasably engageable with the coupling means to retract said bolt members to their unlatching positions upon pivoting of the lever from a rest position, spring means for retarding the abutment means and lever to the rest position independently of said coupling means, a detent movable with said coupling means, a keeper member movable into and out of detent holding position for holding the detent in position to maintain said bolt members in their unlatching positions, and a shiftable member engageable with a part of the vehicle body upon unfolding of the top to the cover position for moving said keeper member out of the detent holding position.

9. In a latch means for a convertible top movable between folded and cover positions with respect to a vehicle body, a pair of oppositely shiftable bolt members for latching said top in the cover position, spring means associated with said bolt members for urging the same into latching positions, pivotally mounted coupling means interposed between and pivotally connected to adjacent portions of said bolt members, a pivotal control lever for said coupling member and mov-

11

able from a rest position to actuate the coupling member and thereby retract said bolt members to their unlatching positions, and spring means yieldingly urging said lever to its rest position independently of movement of the bolt members from their unlatching positions.

10. In a latch means for a convertible top movable between folded and cover positions with respect to a vehicle body, a pair of oppositely shiftable bolt members for latching said top in the cover position, spring means associated with said bolt members for urging the same into latching positions, pivotally mounted coupling means interposed between and pivotally connected to adjacent portions of said bolt members, a pivotally mounted control lever, link means connecting the lever and coupling means to actuate the latter to retract said bolt members to their unlatching positions upon pivoting of the lever from a rest position, spring means acting on said link means to return the lever to its rest position upon release of the lever.

11. In combination with latch means for a convertible type vehicle top movable between the folded and cover positions with respect to the vehicle body, the latch means having an abutment and being shiftable to and from a latching position for latching the top in the cover position, resilient means yieldingly urging the latch means to the latching position, means for shifting the latch means from the latching position comprising a manually shiftable control mechanism having a portion releasably engageable with said abutment and shiftable in one direction into driving engagement therewith, a detent movable with the latch means, a keeper movable into and out of detent holding position and engageable therewith the detent to block shifting of the latch means to the latching position, and a shiftable member engageable with a part of the vehicle upon unfolding of the top to the cover position for moving the keeper out of the detent holding position.

12

5 12. In combination with latch means for a convertible type vehicle top movable between folded and cover positions with respect to the vehicle body, the latch means having an abutment and being shiftable to and from a latching position for latching the top in the cover position, resilient means yieldingly urging the latch means to the latching position, a manually shiftable control mechanism releasably engageable with said abutment and shiftable in one direction into driving engagement therewith for shifting the latch means to an unlatching position, said mechanism being movable out of said driving engagement upon shifting oppositely to said one direction, said control mechanism including a handle movable to and from a rest position upon shifting of said mechanism in said one direction or the opposite respectively and being thereby returnable to the rest position independently of movement of the latch means, spring means yieldingly urging the handle to its rest position, a detent movable with the latch means, a keeper movable into and out of detent holding position and engageable therewith the detent to hold the latch means in the unlatching position, and a shiftable member engageable with a part of the vehicle upon unfolding of the top to the cover position for moving the keeper out of the detent holding position.
